UNITED STATES PATENT OFFICE.

DAVID ERTER, OF SPRINGFIELD, OHIO.

GROUND-BREAKING DEVICE.

1,147,492.

Specification of Letters Patent. Patented July 20, 1915.

Application filed June 6, 1914. Serial No. 843,381.

To all whom it may concern:

Be it known that I, DAVID ERTER, a citizen of the United States, residing at Springfield, in the county of Clark and State of 5 Ohio, have invented certain new and useful Improvements in Ground-Breaking Devices, of which the following is a specification.

My invention relates to improvements in ground breaking devices, and more particularly to ground breaking devices capable of 10 being attached to a road roller.

The object of my invention is to provide an attachment which will be effective in operation and simple in construction.

15 A further object of the invention is to provide effective means for applying pressure to the breaker when in operation and also for raising and holding the same in operative position during transportation.

20 A further object of the invention is to provide a ground breaking device which may be readily attached to a road roller which is in service so that it will be unnecessary to take the roller out of service for a 25 material length of time and send it to a shop to have the ground breaking device attached thereto.

A further object is to provide a ground 30 breaking device, for attachment on a road roller, which shall be so connected to the roller that it has a direct dragging action thereon and is provided with a cushioning device whereby any lifting action of the ground on the breaking device will be taken 35 up by the cushioning device, thus relieving the roller of the excessive jarring and vibration which the breaking device is subjected to.

40 A further object is to provide a ground breaking device, for attachment on a road roller which shall be so connected to the roller and with a cushioning device that the latter will exert a substantially uniform pressure to force the breaker into the ground regardless of the depth of penetration.

45 In the accompanying drawings:—Figure 1 is a side elevation of the rear portion of a road roller showing my improved devices applied thereto. Fig. 2 is a section on the 50 line 2—2 of Fig. 1. Fig. 3 is a side view of the piston guide head. Fig. 4 is a section on

the line 4—4 of Fig. 5. Fig. 5 is a rear elevation of the devices shown in Fig. 1. Fig. 6 is a section on the line 6—6 of Fig. 1.

Like parts are represented by similar characters of reference in the several views.

In the said drawings, 1 represents the tank of a road roller and 2 the rear wheels. The ground breaking device proper consists of a series of spikes 3 clamped between two channel bars 4 by the bolts 5. There is usually attached to the back of the tank 1, a draw bar 26 which has several holes therein for the attachment of chains or other hauling devices. In the present case there is secured to the draft bar 26, by bolts 26' which engage the holes in the draft bar, a pair of brackets 6, having bearings 7 in which bearings is rotatably mounted a transverse shaft 8; the brackets being braced by the brace- 70 rods 6^a, secured at their lower ends to the bearings 7 and at their upper ends to the tank. A pair of drag-bars 9, securely bolted to the channel bars 4, are keyed at their forward ends to the transverse shaft 8, as 75 shown in detail in Fig. 4, the keys being indicated by 10. One of the drag-bars 9 has an upwardly extending crank arm 11, pivotally connected at its upper end to a link 12 which link 12 has its forward end pivotally 80 connected to the rod 13 of a piston (not shown) located in the cylinder 14, which cylinder is secured to the side of the tank 1. The end of the piston rod 13 has firmly secured thereto a head 15, the upper end of 85 which is provided with an integrally formed sleeve 16 arranged to slide on the rigid guide rod 17 which is secured firmly to the side of the tank by the brackets 18. The lower end of this head 15 has oppositely extending trunnions 19 to which the link 12 is pivoted; the link 12 being preferably formed of two members spaced apart by the blocks 12^a and rigidly bolted together by bolts 12^b to permit 90 it to be readily assembled, the crank arm 11 being pivoted between these members, the rear ends of which are provided with a series 95 of holes 20 to receive the pivot bolt 21 so that the parts may be adjusted to regulate the depth of digging and also the height to 100 which the devices may be raised for transportation.

The cylinder 14 may be a steam cylinder which receives a supply of steam from the boiler of the machine through a supply pipe 22 leading through a valve 23 and pipes 24 to either end of the cylinder. When an explosive engine is used as the propelling power, the cylinder may be an air cylinder, receiving air under pressure from the tank 25, shown in dotted lines, in which air may be maintained under pressure from any suitable air pump (not shown) and having a pipe 25^a leading to the valve 23.

When it is desired to operate the breaking devices, fluid is admitted in the forward end 15 of the cylinder so as to drive the piston to the rear end thereof and hold the parts in the position shown in full lines in Fig. 1, the valve 23 being allowed to remain in position to maintain the cylinder 14 in constant 20 communication with the boiler or tank 25, as the case may be. To raise the breakers to the position shown in dotted lines in Fig. 1 fluid is admitted to the rear end of cylinder 14.

25 By this construction effective means are provided for applying pressure to the breaking devices and for raising them to inoperative position. This fluid operated pressure device also permits the breaking devices and the machine to which they are attached to rise and fall independently of each other to compensate for irregularities in the ground over which they are traveling; this movement, of course, being against the pressure of the fluid in the cylinder, which, on account of being in constant communication with the supply, will be substantially uniform.

From the foregoing it will be apparent 30 that the ground breaking mechanism may be readily attached to the machine, since it is only necessary to bolt the brackets 6 to the draw bar 26 and drill holes in the tank 1 for securing the cylinder 14 and bracket 18. 35 The arrangement of the drag-bar 9 produces a direct drag on the back of the machine and any up and down movements of the channel-bars 4 will result in oscillation about the axis of shaft 8, and a cushioning movement 40 of the piston in cylinder 14, thereby relieving the machine of much jolting and vibration. On account of the up and down movement of the channel-bars 4 being about the axis of the shaft 8 and because of the character 45 of the connection between the arm 11 and the piston-rod 13, the pressure on the piston will result in a substantially uniform force being exerted on the spikes to force them into the ground, irrespective, of the 50 depth at which they are working.

Having thus described my invention, I claim:—

1. In combination with a self-propelling road machine having front and rear wheels, 55 of a shaft attached to the rear of said ma-

chine, rearwardly extending drag-bars carried by said shaft, ground breaking spikes carried by said drag-bars and downwardly and forwardly inclined relative thereto, an upwardly projecting arm rigid with said drag-bars and having its upper end so arranged as to swing substantially horizontally, and cushioning means mounted on said machine, independently of the means for attaching said shaft to the machine, and operatively connected with said arm. 70

2. In combination with a self-propelling road machine, a pair of bearing brackets secured on the rear thereof, a horizontal shaft rotatably mounted in said brackets, drag-bars carried by said shaft, forwardly and downwardly inclined ground breaking spikes carried by said drag-bars at the rearward ends thereof, an arm rigid with said drag-bars and projecting upwardly from said shaft, and combined positioning and cushioning means mounted on the machine, independently of said brackets, and operatively connected with the upper end of said arm whereby said spikes may be forced into the ground by a substantially horizontal force applied to said arm, the bars being so arranged that the vertical re-action of the ground on said spikes is opposed by the weight of said machine, exerted through 90 said brackets. 95

3. In combination with a self-propelling road machine having front and rear wheels and also having a draw-bar secured to the rear thereof, of a ground breaking device 100 pivotally mounted on said draw-bar and including an upwardly projecting arm and forwardly and downwardly inclined spikes, said device being rigid against all movement except rocking on its pivotal mounting, 105 cushioning means mounted on said machine, above and independently of said draw-bar, for the purpose of forcing and holding said spikes into the ground and also cushioning of upward movements of said spikes, and unyielding connections between said arm and said cushioning means arranged to transmit forces from one to the other in a substantially uniform ratio for different operating positions of the parts, said cushioning means and connections permitting said machine to freely rise and fall relatively to 110 said ground breaking device. 115

4. In combination with a self-propelling road machine having front and rear wheels and also having a draw-bar secured on the rear thereof, of a ground breaking device pivotally mounted on said draw-bar and rigid against all movement except rocking on its pivotal mounting, said ground breaking device including forwardly and downwardly inclined digging spikes, cushioning means mounted on said machine, independently of said draw-bar, for the purpose of forcing and holding said spikes into the 120 125 130

ground and also cushioning all upward movement of said spikes, and adjustable unyielding connections between said cushioning means and said ground breaking device
5 adapted to transmit force in a substantially uniform ratio for different positions of the parts.

In testimony whereof, I have hereunto set my hand this 2nd day of June 1914.

DAVID ERTER.
